UNITED STATES PATENT OFFICE

126,642

DESIGN FOR A TEXTILE FABRIC

Arnold Salzenstein, Peoria, Ill.

Application February 1, 1941, Serial No. 98,630

Term of patent 3½ years

To all whom it may concern:

Be it known that I, Arnold Salzenstein, a citizen of the United States, residing in the city of Peoria, State of Illinois, have invented a new, original, and ornamental Design for a Textile Fabric, of which the following is a specification, reference being had to the accompanying drawing, forming part thereof.

The figure is a plan view of a textile fabric showing my design.

I claim:

The ornamental design for a textile fabric, as shown.

ARNOLD SALZENSTEIN.
